[57] CLAIM

The ornamental design for a compartmented pan, substantially as shown and described.

DESCRIPTION

FIG. 1 is a top plan view of a compartmented pan showing my new design;

FIG. 2 is a bottom plan view thereof;

FIG. 3 is a front elevational view thereof, the rear view being substantially a mirror image thereof;

FIG. 4 is an end elevational view thereof, the opposite end being substantially a mirror image thereof;

FIG. 5 is a sectional view taken along line V—V of FIG. 1, and

FIG. 6 is a sectional view taken along line VI—VI of FIG. 2.
